IDENTIFICATION TAG

Erial B. Otis, Chicago, Ill., assignor to The Wallace
Press, Chicago, Ill., a corporation of Illinois

Application February 16, 1942, Serial No. 431,123

2 Claims. (Cl. 282—11.5)

This invention relates to form packs for use in typewriting, addressing and other printing machines, including automatic machines, for rapidly entering data and other inscriptions upon successive forms.

The main objects of this invention are to provide an improved form of identification tags in continuous strip arrangement and adapted to be fed in succession to typewriting and other data-imprinting machines equipped with feed devices of pin-type; to provide a paper tag of this kind sufficiently flexible to pass readily around the platen roller of a typewriting machine and yet appropriately reinforced and perforated to receive a tie cord by means of which it may be attached to an object for the purpose of identifying its nature, ownership, use, destination, etc.; and to provide a tag structure of this kind in which the reinforcement for attachment of the tie cord contributes to the accurate feeding of the tags to a printing machine equipped with feed mechanism of the pin-type. A further object is to provide an improved manifolding pack embodying such tags.

Specific embodiments of this invention are shown in the accompanying drawings in which:

Figure 1 is a perspective view of a form pack consisting of a continuous strip provided with transverse severance lines defining form units appropriate for use as identification tags and having one of its longitudinal margins reinforced and perforated to serve as a feed-band.

Fig. 2 is a fragmentary detail of the strip showing a face view of the forms.

Fig. 3 is a similar detail showing the form of the strip at a stage of its manufacture that precedes the folding of one of its longitudinal marginal portions to form the reinforced feed band.

Fig. 4 is an enlarged transverse sectional detail taken on the line 4—4 of Fig. 2, the paper thickness being exaggerated for clearness.

Fig. 5 is a detail of a separate reinforcing strip appropriate for attachment to a form blank of the form illustrated in Fig. 6 in a modified embodiment of the invention shown in section in Fig. 7.

Fig. 8 is a perspective view of an individual identification tag after it has been torn from the strip and equipped with its tie cord, or wire.

Fig. 9 is a fragmentary top view of a modified embodiment in which the tag strip is assembled with other record and carbon sheets in manifolding relation for use under circumstances where certain of the data that appear both on the records and on the tags may be applied in a single manifolding operation.

Fig. 10 is a transverse section of the same taken on the line 10—10 of Fig. 9.

Fig. 11 is a top face view of a single tag unit

of the type employed in the manifolding assembly of Figs. 9 and 10.

In the form shown in Figures 1 to 4 inclusive, the form pack consists of a continuous traveler strip 1 of cardboard or calendered paper, preferably of about the thickness of the paper used in postal cards, having a series of uniformly spaced lines of severance 2 extending transversely across the strip so as to divide the same into a succession of unit form lengths 3.

One of the marginal edges of the strip is provided with pin-type feed apertures 4, with respect to which the severance lines 2 are so located that certain of these pin-type feed apertures, designated 41, will be located at approximately the mid-point of their respective form lengths when these are torn from the strip to form individual tags. To accomplish this end, the unit form width, or interval between successive severance lines, is an exact multiple of the unit space between successive feed apertures. If this multiple is an even number, then the lines of severance 2 will coincide with the centers of the adjacent feed apertures; and if this multiple is an odd number, then the lines of severance will bisect the spaces between pairs of adjacent pin-type feed apertures.

In the form shown in Figures 1 to 4 inclusive, and Fig. 8, the marginal feed-band is made by folding an edge portion 5 of the strip back upon the body of the strip 1 in the manner illustrated in Fig. 4. To this end, the strip is originally cut to a width corresponding to its finished width plus the width of the feed-band portion and has spaced inwardly from its edge a fold line 6, preferably weakened by scoring or slitting so that the marginal portion 5 will lie flat against the body to which it is pasted, so that the feed-band will be of double thickness. In making this embodiment of the invention, it is preferred to slit or perforate the severance lines 2 as well as to slit or score the line 6 before the two plies of the feed-band are folded upon each other and pasted together.

Likewise, it is preferred to punch the perforations 4 in two rows as shown in Fig. 3 in which the perforations are located with respect to the fold line 6 and to each other so as to exactly register when the fold is completed. By this arrangement, the adequate weakening of the severance lines between tag forms is assured.

The sequence of operations may, of course, be modified so that the folding of the margin of the strip and the gluing of the flap 5 to the body portion 1 is performed in advance of the punching of the feed apertures 4 and the punching of the severance line apertures 2. If the gluing is the final operation, as hereinabove described, then it is preferred that the adhesive be applied in two narrow bands as illustrated in Fig. 3, so as to

avoid having it enter the preformed feed apertures 4; otherwise it may be applied as a single band of adhesive equal to the width of the flap 5. When the folding down and gluing of the flap 5 precedes the punching operations, all that is necessary is to punch only a single line of apertures 4 in the reinforced marginal strip and to arrange the cutting wheels that weaken the severance lines, so that the reinforcing of the marginal strip will not interfere with the tearing off of the tags on their severance lines.

In the form shown in Figures 5, 6 and 7, the original traveler strip 1.1 is made of a width corresponding to its final width with a single row of perforations 4 forming the pin-type feed apertures of the feed-band, and the reinforcement is a separate strip 5.1 which is provided with pin-feed perforations 4 like those in the body of the strip 1.1 and this reinforcing strip is pasted upon the margin of the strip 1.1 with its perforations 4 in registry with the perforations 4 of the body strip 1.1.

In the form shown in Figure 5, this reinforcing strip 5.1 is of a width double that of the feed-band of the body strip 1.1 and is provided with a weakened fold line 6.1 running along its longitudinal center line. In this form, as shown in Figure 7, the reinforcing strip is folded upon itself along the longitudinal line 6.1 and then applied and affixed by means of adhesive to the body strip in such position that it embraces the feed-band of the body strip 1.1 as shown in Figure 7. In manufacturing this embodiment of the invention, it is preferable to paste the reinforcing strip 5.1 upon the marginal edge of the body strip 1.1 prior to the punching operations.

By utilizing the reinforced feed-band apertures as the eyelets which receive the ties, it is possible to use a single tie cord 7, as shown in Fig. 8, in the central aperture 4.1 for attaching the tag to an object that it is to identify in the manner usual with identification tags, or it is possible to use a pair of tie cords in spaced apertures 4 and thereby fasten the tag to spaced points of attachment on the article to which it is affixed so that the tag will always remain face outward.

In the form shown in Figs. 9, 10 and 11 the strip of identification tags 1.2 is combined with record strips 9 and carbon-coated transfer strips 10 in an appropriate assemblage for continuous manifolding operation. In the form shown, the tag strip 1.1 has the reinforced feed-band 5 with the pin-type feed apertures 4 on one margin and has its other margin extended to form a binding stub 11 to which the record and carbon traveler strips may be fastened by adhesive or stitching or stapling. This binding stub is also provided with pin-feed-band apertures 4 for cooperation with pin-type feed devices of typewriting machines.

In the drawings, this fastening means is shown in the form of staples 12 and all of the strips of the pack are provided with stub-severance weakened lines 13 so that they may be separated either individually or as a group from the stubs in any sequence that might best suit the needs of a particular individual job.

It will be understood that the printed matter on the record strips and the identification tag strip would be adjusted so that in filling out the records certain of the information on the record sheets will be simultaneously transferred to the identification tags and that these may then be separated and certain other information be added

to either of them as the individual circumstance may require and this is well understood in the art to which this invention relates.

In Fig. 11 the printing on the identification tag 5 is indicated in an arrangement appropriate for use in labeling machine parts for mass assembly operations.

The term cardboard, as herein employed in the claims, is not intended to be limited to a paper product but is intended to include any material that is appropriate for use in tags of this general type, as for example, fabrics filled with appropriate materials to give stiffness thereto, sheets of plastic and analogous materials.

15 It is preferred to assemble the strips in pack form as illustrated in Fig. 1 by folding the strip in zigzag fashion, as illustrated in Fig. 1, and in some instances where machines are used for separating the strips into their individual units after 20 the writing operation has been completed, it will be sufficient to employ perforated severance lines 2 only at the points where the folds of the zig-zag formed pack occur and therefore it is to be understood that the term "unit intervals" as 25 hereinafter used in the claims is intended to be sufficiently comprehensive to include units of multiple tag width as well as units of individual tag width or form length.

It is to be understood that details of the specific embodiments of the invention herein shown and described may be altered or omitted without departing from the spirit of this invention as defined by the following claims.

I claim:

35 1. A form pack for typewriting machines, comprising a continuous strip of cardboard having weakened severance lines extending transversely across it at intervals defining successive tag units, said strip having along one longitudinal 40 margin a line of severance defining a feed-band, said strip having along its other longitudinal margin a reinforcing marginal strip fastened thereto, a plurality of manifolding record strips overlying said cardboard strip being fastened to 45 said first named feed-band and having weakened lines of severance extending transversely across them adjacent the transverse lines of severance of said cardboard strip, whereby superposed units of said strips may be torn from the 50 pack and retained in their manifolding relation to each other by said marginal fastening.

2. A form pack for typewriting machines, comprising a continuous strip of cardboard having weakened severance lines extending transversely across it at intervals defining successive tag units, said strip having along one longitudinal margin a line of severance defining a feed-band, said strip having along its other longitudinal margin a reinforcing marginal strip fastened thereto, a 55 plurality of manifolding record strips overlying said cardboard strip being fastened to said first named feed-band, and having weakened lines of severance extending transversely across them adjacent the transverse lines of severance of said 60 cardboard strip, whereby superposed units of said strips may be torn from the pack and retained in their manifolding relation to each other by said marginal fastening, said overlying 65 manifolding strips being narrower than said cardboard strip and having free longitudinal margins spaced inward from said reinforced margin of said cardboard strip.

ERIAL B. OTIS.
